AUTOMATIC BENDING MACHINE

Andrew L. Froedge, Oak Lawn, Ill.

Application September 12, 1952, Serial No. 309,268

5 Claims. (Cl. 153—40)

1

This invention relates to an automatic bending machine, and more especially to a head structure for an automatic bending machine. The automatic bending machine and head structure of this invention can be advantageously employed for forming bends in various types of elongated metal stock such as rods, angles, channels, tubes, flat stock, V-shaped stock, etc. However, the structures contemplated by this invention have particular utility for use in bending tubes or pipes of generally circular cross-section.

It is a general object of this invention to provide an automatic bending machine of novel design which can be operated at the maximum speed at which the pieces of elongated metal stock can be fed. More specifically in this connection, it is an object of this invention to provide an automatic pipe bending machine which is capable of making up to at least 1200 bends per hour on a wide variety of different diameters of pipe. It is a further object of this invention to provide an automatic bending machine, and more specifically a head structure therefor, which is particularly adapted to heavy duty work, for example, bending steel tubing of up to at least 6 inches in diameter. It is a further specific object of this invention to provide a novel head structure for an automatic bending machine which substantially prevents slippage between the main die wheel and the clamping die even though the faces of the die wheel and clamping die have become appreciably worn. Another specific object is to provide a die wheel of novel configuration arranged to coact with the clamping die to tightly clamp the work piece over a substantial length thereof. It is also an object of this invention to provide means for applying increased clamping power between the die wheel and clamping die to firmly hold the work piece while the bend is being formed therein. Still another object of this invention is to provide a smoothly operating head structure for an automatic bending machine, which operates without jerking or binding on both the bending and return movements, even though a large clamping pressure is applied. Another specific object of the invention is to provide an automatic pipe bending machine which can be adjusted for the bending of various diameters of pipe. Further objects and advantages will appear as the specification proceeds.

My invention is shown in an illustrative embodiment in the accompanying drawings, in which—

Figs. 1 to 3 are fragmentary operational plan views of a bending machine head structure em-

2

bodying the principles of this invention, Fig. 1 showing the clamping die in retracted position with respect to the die wheel, Fig. 2 showing the clamping die in advanced position at the beginning of the bending operation, and Fig. 3 showing the position of the clamping die and die wheel at the completion of the bending operation; Fig. 4, an enlarged plan view of the bending machine structure illustrated in part in Figs. 1 to 3; Fig. 5, a cross-sectional view of the bending machine head structure taken on line 5—5 of Fig. 4; Fig. 6, an end elevational view of the head structure looking toward the right-hand end of the structure represented in Fig. 5; Fig. 7, a cross-sectional view looking in the same direction as the view of Fig. 6 taken on line 7—7 of Fig. 5; and Fig. 8, a fragmentary bottom cross-sectional view taken on line 8—8 of Fig. 5.

In one of its embodiments, this invention contemplates in an automatic bending machine, the combination of a frame, a main shaft carried by the frame having a die wheel affixed thereto, a hollow case pivotally mounted on the main shaft inwardly of the die wheel and projecting laterally from the shaft, a slideably mounted clamping die carried by the case and arranged for advancing and retracting movements with respect to the die wheel, and means for actuating the clamping die, including means for advancing and retracting the clamping die, and means for rotating the clamping die about the die wheel for a part of a revolution when the clamping die is in its advanced position. In this particular combination, the provision of a hollow case pivotally mounted on the main shaft is felt to be of particular importance for accomplishing the above objects. Further specific features and the advantages resulting therefrom will subsequently be discussed in detail.

Turning now to the drawings, and more particularly to Figs. 4 and 5 thereof, there is shown an automatic bending machine having a frame A providing spaced, horizontally-extending, upper and lower frame plates 10 and 11. The forward end portions of frame plates 10 and 11 rotatably receive vertically-extending main shaft 12, as shown more clearly in Fig. 5. In the illustration given, cone bearings 13 and 14 are respectively provided in plates 11 and 10 for rotatably receiving shaft 12.

The upper end of main shaft 12 is equipped with an integral collar 15 spaced from the upper end of shaft 12 to provide a hub portion 16, which in turn is provided with a threaded bore as indicated at 17, and with a cross slot as indicated at

18. The lower end of shaft 12 provides a reduced portion 19.

A hollow case, indicated generally at B, is pivotally mounted on main shaft 12. In the illustration given, case B, as shown more clearly in Figs. 6 and 7, is provided with a top wall 20, a bottom wall 21, and side walls 22 and 23, which are rigidly locked together. Upper plate 20 is rotatably received on hub portion 16 of shaft 12 and lower plate 21 is rotatably received on reduced portion 19 of shaft 12. It will be noted that case B extends laterally from shaft 12, and that top wall 20 provides a bearing surface beneath die wheel 24. Die wheel 24 is rigidly affixed to the top of shaft 12 by means of a cross-tongue 25 interlocking with slot 18, and a headed stud 26 extending through an opening in die wheel 24 and threadedly seated within bore 17. It will be noted that die wheel 24 is coaxially aligned with shaft 12.

A double sprocket, consisting of an upper sprocket 27 integrally connected to a lower sprocket 28, is rotatably mounted on an intermediate portion of shaft 12. If desired, pin bearings 29 can be employed to provide the rotatable mounting. Means is provided for driving one of these sprockets. In the illustration given, this means consists of a chain 30 passing around upper sprocket 27 and extending rearwardly between frame plates 10 and 11, as shown more clearly in Fig. 4. At a spaced distance from sprocket 27 and in alignment therewith, there is provided a guide sprocket 31 which is rotatably mounted on a shaft 32 supported by plates 10 and 11. A hydraulic cylinder 33 is fixedly mounted intermediate sprocket 27 and sprocket 31. Cylinder 33 is provided with a double-acting piston 34 which has connecting rods 35 and 36 extending respectively from each side thereof through the adjacent ends of cylinder 33. The projecting end portions of connecting rods 35 and 36 are attached to the ends of driving chain 30, for example, as indicated at 37.

The bearing plate provided by upper wall 20 of case B is equipped with an elongated slot 38 which extends outwardly from die wheel 24, as indicated in Fig. 4. The sides of slot 38 preferably taper upwardly and inwardly, as indicated in Fig. 7, and one side thereof can be provided with a gib or spacer 39. Slot 38 preferably receives the tapered head of a slide 40 in dovetail relation so that slide 40 moves back and forth within slot 38. In the illustration given, retaining plates 41 and 42 are provided for holding the head of slide 40 within slot 38, as indicated more clearly in Figs. 6 and 7.

A clamping die 43 is slideably mounted on the upper surface of bearing plate 20 over slot 38 and is rigidly connected to slide member 49 by means of bolts 44, and is interlocked therewith by providing cross-tongues 45 which are received within the cross-slots 46 in the top of slide 40. Preferably, as shown more clearly in Fig. 5, the top of slide 40 is provided with a plurality of spaced cross-slots 46 arranged to permit clamping die 43 to be shifted to various positions on slide 40, thus varying the outermost point of retraction of clamping die 43 with respect to die wheel 24.

The laterally-extending portion of case B is provided with a rotatably mounted auxiliary shaft 47 in spaced parallel alignment with main shaft 12. In the illustration given, as illustrated more clearly in Figs. 5 and 7, case B is provided with an intermediate support plate 48 extending between the side walls 22 and 23 thereof, and with a hub support member 49 secured to lower

plate 21. Shaft 47 is rotatably mounted within plate 48 and hub 49 by means of in bearings 50 and 51.

Means are provided for driving shaft 47 consisting of a sprocket 52 rigidly mounted thereon between plate 48 and hub 49, and having an endless driving chain 53 extending there-around and around lower sprocket 28 on main shaft 12.

Crank means are preferably provided for advancing and retracting clamping die 43 relative to die wheel 24, said crank means being operated by the rotation of shaft 47 and, in turn, operating slide 40. In the illustration given, auxiliary shaft 47 is equipped at its top or upper end with an integral head 54 providing an upwardly-extending eccentric pin 55. Pin 55 pivotally carries one end of link 56, and the other end of link 56 is pivotally connected to slide 40 by means of pin 57. The lower end of pin 57, as seen more clearly in Fig. 5, projects below link 56 and is supported by L-shaped bracket 58. The outer end of bracket 58 is rigidly locked to the outer end of slide 40 by means of pin 59 and bolt 60. These members are arranged so that the revolution of auxiliary shaft 47 for part of a revolution in one direction advances clamping die 43, while upon shaft 47 reversing its direction of rotation, clamping die 43 is retracted and returned to its initial open position.

As seen more clearly in Fig. 4, die wheel 24 is preferably equipped with a tangential extension 61 providing a substantially straight clamping face 62 confronting the straight clamping face 63 of clamping die 43 and coacting therewith.

Main shaft 12 is preferably equipped with means for exerting a selectively predetermined frictional drag on the rotation of the shaft. This can be accomplished by providing an adjustable preloaded brake coacting with main shaft 12. Among the results accomplished by this are that shaft 12 and die 24 are prevented from rotating until the work piece has been firmly clamped between die faces 62 and 63. Another advantage is that smooth, non-jerky operation is obtained on both the bending and return movements of die wheel 24. In the illustration given, there is provided a brake drum 64, which is keyed to main shaft 12, as shown more clearly in Fig. 5. Brake drum 64 is positioned immediately below upper frame plate 10, which provides on each side of the brake drum downwardly-extending brake band supports 65 and 66. As shown more clearly in Fig. 8, pin 65 receives bracket 67 which is rigidly attached to a brake band loop 68 having its free ends provided with attachment eyes 69 and 70. Eyes 69 and 70 respectively receive the ends of J-bolts 71 and 72, which are spring-tensioned and extend through support projection 66. Between brake band 68 and the frictionally-engaged outer surface of brake drum 64 there is provided a brake lining 73.

Operation

The operation of the automatic bending machine of this invention is illustrated in Figs. 1 to 3. Fig. 1 shows the members in their starting position with clamping die 43 fully retracted and with die faces 62 and 63 in facing relation. The work stock to be bent, in this case a pipe P, has been fed into engagement with face 62 of die wheel 24. The rearward portion of pipe P rests against abutment or stop 74 to prevent the rearward portion of the pipe from rotating during the bending operation. Alternately, a feed tube of the conventional type can be provided for receiving the rearward portion of pipe P.

Piston 34 within cylinder 33 is then forced rearwardly by hydraulic fluid entering through pipe 75 which rotates sprockets 27 and 28 by means of chain 38 passing around upper sprocket 27. This in turn rotates sprocket 52 and auxiliary shaft 47 by means of endless chain 53. The rotation of shaft 47 operates the crank assembly including head 54, link 56, and slide 40, so that clamping die 43 is advanced toward die wheel 24. This movement continues until the position is reached as indicated in Fig. 2, at which point pipe P is clamped between clamping die 43 and die wheel 24. From this point on, further rotation of shaft 47 produced in the manner described, causes case B to pivot on main shaft 12 until the position illustrated in Fig. 3 is reached. During this rotation, maximum clamping power continues to be applied between clamping die 43 and die wheel 24 so that pipe P is, in effect, wrapped around die wheel 24 to form the desired bend in pipe P.

On the return movement from the position indicated in Fig. 3, the piston 34 of cylinder 33 is driven in the reverse direction by fluid entering through pipe 76 which in turn rotates sprockets 27 and 28, sprocket 52, and shaft 47 in the opposite direction. This movement causes the crank assembly to retract clamping die 43 so that it disengages from pipe P and permits the members to return to the position illustrated in Fig. 1, after the manual removal of pipe P by the operator.

While in the foregoing specification a specific embodiment of this invention has been described in considerable detail for purpose of illustration, it will be readily apparent to those skilled in the art that many of the details set forth can be varied widely without departing from the spirit of the invention.

I claim:

1. In an automatic bending machine, the combination of a frame, a main shaft carried by said frame having a coaxially aligned die wheel affixed to a projecting end thereof, two rigidly connected sprockets rotatably mounted on said main shaft, means for driving one of said sprockets for a part of a revolution first in one direction and then in the other, a hollow case pivotally supported on said main shaft and projecting laterally therefrom, said case providing a bearing plate inwardly of said die wheel having a slot therein extending outwardly from said die wheel, an auxiliary shaft rotatably mounted in said case in spaced parallel alignment with said main shaft and having its upper end terminating at a spaced distance from said slot, a sprocket wheel rigidly mounted on said auxiliary shaft, chain means drivably connecting said auxiliary shaft sprocket with the other sprocket on said main shaft, a clamping die slideably mounted on said bearing plate over said slot therein in alignment with a clamping face of said die wheel, and crank means connecting said upper end of said auxiliary shaft with said clamping die through said slot for advancing and retracting said clamping die.

2. In an automatic bending machine, the combination of a frame, a vertically-extending rotatably mounted main shaft carried by said frame, a coaxially aligned die wheel rigidly connected to the top of said main shaft for rotation in unison therewith, two rigidly connected sprockets rotatably mounted on said main shaft, means for driving one of said sprockets for a part of a revolution first in one direction and then in the other, a hollow case pivotally supported on said main shaft with said sprockets there-with-

in, said case extending laterally from said main shaft and providing a horizontal bearing plate beneath said die wheel, said bearing plate having a slot therein extending outwardly from said die wheel, an auxiliary shaft rotatably mounted in said case in spaced parallel alignment with said main shaft and having its upper end terminating at a spaced distance below said bearing plate slot, a sprocket wheel rigidly mounted on said auxiliary shaft, chain means drivably connecting said auxiliary shaft sprocket with the other sprocket on said main shaft, a clamping die slideably mounted on said bearing plate for advancing and retracting movements relative to said die wheel along the line of said bearing plate slot, said clamping die having a die face confronting said die wheel, and crank means connecting the upper end of said auxiliary shaft with said clamping die through said bearing plate slot, said crank means being arranged to direct the advancing and retracting movements of said clamping die.

3. The combination of claim 2 which is characterized by the further fact that said main shaft is equipped with means for exerting a selectively predetermined frictional drag on the rotation of said main shaft.

4. The combination of claim 2 in which said means for driving one of said sprockets for part of a revolution first in one direction and then in the other comprises a guide sprocket rotatably mounted at a spaced distance from said driven sprocket and in alignment therewith, a hydraulic cylinder positioned between said sprockets having a double-acting piston therein, connecting rods extending from each side of said piston through the adjacent end of said cylinder, and a chain having its opposite ends attached to the projecting ends of said connecting rods and passing around both of said sprockets.

5. In an automatic bending machine, the combination of a frame providing vertically-spaced horizontally-extending plate members, a vertically-extending rotatably mounted main shaft carried by said plate members and projecting upwardly and downwardly therebeyond, a hollow case member having upper, lower, and side plates, the upper plate of said case member being pivoted on the upwardly-projecting portion of said main shaft and the lower plate of said case member being pivoted on the downwardly-projecting portion of said main shaft, the upper plate of said case member providing a bearing plate, a coaxially aligned die wheel rigidly connected to the top of said main shaft above said bearing plate, a double sprocket rotatably mounted on said shaft, means for driving one of said sprockets of said double sprocket for part of a revolution first in one direction and then in the other, said bearing plate having a slot therein extending outwardly from said die wheel, an auxiliary shaft rotatably mounted in said case in spaced parallel alignment with said main shaft and having its upper end terminating at a spaced distance below said bearing plate slot, a sprocket wheel rigidly mounted on said auxiliary shaft, chain means drivably connecting said auxiliary shaft sprocket with the other sprocket of said double sprocket, a clamping die slideably mounted on said bearing plate for advancing and retracting movements relative to said die wheel along the line of said bearing plate slot, a slide member slideably mounted within said slot and carrying said clamping die, and crank means connecting the upper end of said auxiliary shaft with said slide

member, said crank means being arranged to direct the advancing and retracting movements of said slide member and clamping die.

ANDREW L. FROEDGE.
